ATTORNEY

UNITED STATES PATENT OFFICE

HENRY J. GAISMAN, OF NEW YORK, N. Y., ASSIGNEE, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed June 29, 1928. Serial No. 289,116.

My invention relates to improvements in the class of safety razors in which a blade is clamped between a guard member and a backing member for shaving.

5 An object of my invention is to provide improved means to retain the blade edge in shaving relation to the guard teeth or comb irrespective of the action of the backing member, while permitting the blade to be properly 10 clamped between the guard and backing members.

In carrying out my invention I provide a razor having guard and backing members, with movable means carried by one of said 15 members and operative in openings in a blade between said members to engage edges of said openings to retain the blade in shaving relation to the guard, said means being movable between said members and adapted to project 20 through the blade when the latter is placed upon the corresponding member and to engage the other member and be moved by the latter to permit the members to be clamped upon the blade.

25 My invention also comprises novel details of improvement more fully hereinafter set forth and then pointed out in the claims.

Reference is to be had to the accompanying drawings, in which

30 Fig. 1 is a side view of a safety razor embodying my invention, shown assembled for use;

Fig. 2 is a side view of Fig. 1;

35 Fig. 3 is a plan view with the backing member partly broken;

Fig. 4 is an exploded view, partly in section on line 4, 4, in Fig. 3;

Fig. 5 is a section on line 5, 5, in Fig. 3;

40 Fig. 6 is a section on line 6, 6, in Fig. 2;

Fig. 7 is a detail perspective view, and Fig. 8 is a plan view of the blade.

Similar numerals indicate corresponding parts in the several views.

45 The numeral 1 indicates a guard member, shown provided with comb-like teeth at 1a, in an ordinary way, and at 2 is a backing member, between which members a blade 3 is to be clamped. The blade may have one or more cutting edges 3a. The members 1 and 50 2 may be clamped upon the blade in any de-

sired way, such as by means of a threaded stem or projection 4 on the backing 2 that enters a threaded bore 5 in the handle 6 after passing through an opening 3' in the blade and through an opening 1b in guard member 55 1, in a well known way. The backing member 2 is shown provided with spaced projections or pins 8 that are adapted to pass through openings 3'' in the blade and through openings 1c in the guard member, in 60 an ordinary way. In the class of razor described the openings 1c in the guard member permit some lateral movement of the projections 8 and of the blade, so that the user may have to make an adjustment to assure the required position of the blade edge relatively 65 to the guard teeth for proper shaving.

In accordance with my invention I provide movable projections or guides for the blade at 9, which are carried by and project 70 through one of the members, and through the blade, to be engaged by the other member. The projections or guides 9 are, preferably, resiliently supported. I have shown the projections or guides 9 at the ends of springs 10, and the parts 9 and 10 may be formed from spring wire, bent at the end portions to form the projections 9, (Figs. 6 and 7). By preference the springs 10 are located in longitudinal grooves 11 formed in the under sides of 75 the guard member 1, and the projections 9 pass through holes 12 in guard member 1, (Fig. 7). The springs 10 may be secured to member 1, preferably mid-way of their length, by any suitable means, such as by rivets at 13, (Figs. 6 and 7). In the construction illustrated the projections 9 are arranged in pairs near each end of the guard member 1, the projections of each pair being suitably 80 spaced apart. The openings 3'' in the blade are shown elongated in a transverse direction respecting the cutting edges of the blade, and said openings have corner recesses at 3b, formed between the side walls of the openings and inwardly extending projections 3c, which 85 projections are opposed and spaced apart to permit the passage between said projections of the pins 8 when the parts are assembled, (Figs. 3 and 8).

90 When the parts are dis-assembled the pro- 100

jections 9 project beyond the surface of the guard member upon which the blade is to rest, (Figs. 4 and 7). When the blade is placed upon the guard member said projections enter the corner recesses 3b in the blade, which recesses of each end opening 3" are spaced substantially the same distance apart as the outer sides of the projections 9, so that said projections will fit snugly in the recesses 10 of the corresponding opening, (Fig. 3), and thereby the blade will be set and retained with its cutting edges in proper shaving position respecting the guard teeth. When the backing member 2 is applied upon the blade 15 said member will engage the projections 9, and as the handle is screwed to the stem 4, to clamp the blade between the guard and the backing members, the projections 9 will be pushed back by the backing member but will remain in the openings 3" of the blade, thereby retaining the blade in shaving relation to the guard teeth at all times when the parts are clamped together. The springs 10 permit the described movement of the projections 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550

In accordance with my invention the assembling of the parts is facilitated because the blade may be applied upon the guard member with the projections extending through the blade openings 3", so that the blade will not shift its position upon said member when the backing member is being applied, and in case the latter member should not be accurately placed upon the blade the position of the latter relatively to the guard teeth will not be disturbed. Any shifting of the backing upon the blade will not alter the position of the latter upon the guard member, and the resiliency of the projections 55 or blade guides 9 does not affect the clamping of the members 1 and 2 against the blade nor the bending of the blade between the opposing curved surfaces of said members.

Changes may be made in the details set forth without departing from the spirit of the appended claims.

Having now described my invention what I claim is:

1. A safety razor comprising detachable 60 guard and backing members, the backing member having pins to pass through openings in a blade, means movably carried by and normally projecting from one of said members to enter openings in the blade between said members to retain the blade in shaving

position respecting the guard member irrespective of said pins, and means to detachably retain the members clamped against the blade, said movable means being in position to engage the opposite member to be pushed back by the latter when said members are clamped against the blade. 70

2. A safety razor as set forth in claim 1, in which the movable means is carried by resilient supporting means on the under side 75 of the adjacent member.

3. A safety razor comprising detachable guard and backing members, the backing member having pins to pass through openings in a blade, spaced projections movably carried by and normally projecting from one of the members and operative in openings in the blade between said members to retain the blade in shaving position respecting the guard member irrespective of said pins, and means to detachably retain the members clamped against the blade, said movable means being in position to engage the opposite member to be pushed back by the latter when said members are clamped against the 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550

4. A safety razor as set forth in claim 3, in which the projections are carried by springs secured to the under side of the corresponding member to be moved by the opposing member when said members are clamped against the blade. 95

5. A safety razor comprising detachable guard and backing members, one of said members having spaced holes; guiding projections located and movable in and projecting from said holes to enter openings in a blade between said members, means resiliently supporting said guiding projections upon the corresponding member and away from the blade receiving surface thereof, said projections being in position to engage the other member to permit said members to be clamped, and means to clamp said members against the blade. 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550

6. A safety razor comprising detachable guard and backing members, provided with spaced holes adjacent to opposite ends of one of the members, springs carried by said member away from its blade receiving surface and provided with guiding projections extending through said holes beyond said surface to enter openings in a blade between said members and in position to engage the other member to be pressed back by the last named member to permit said members to clamp against the blade, and means to detachably clamp said members against the blade. 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550
